UNITED STATES PATENT OFFICE.

DAVID H. ROWE, OF OAKLAND, CALIFORNIA.

TRUCK.

No. 814,874.

Specification of Letters Patent.

Patented March 13, 1906.

Application filed January 18, 1905. Serial No. 241,850.

To all whom it may concern:

Be it known that I, DAVID H. ROWE, a citizen of the United States, residing at Oakland, in the county of Alameda and State of California, have invented certain new and useful Improvements in Trucks, of which the following is a specification.

My invention relates to trucks of the kind commonly used for carrying baggage and freight of all kinds; and the object of my invention is to provide a truck which will be capable of carrying its load with the same facility as such loads are carried by the ordinary trucks used, but which, in addition, shall be so constructed as to enable a heavy load to be taken up and down a flight of stairs. The ordinary trucks now in use cannot be employed for the purpose last mentioned, and it is therefore evident that my invention greatly increases the field of usefulness of this particular class of devices.

An embodiment of my invention is shown in the accompanying drawings, in which—

Figure 1 is a side elevation of the whole truck. Fig. 2 is a longitudinal section which shows the opposite side of the truck in inner side elevation. Fig. 3 is a cross-section on the line $z-z$ of Fig. 2 looking in the direction of the arrow which intersects said line.

The frame of the truck is composed of the side rails 1 1 and cross-bars, such as are shown at 2 2. The ends of said rails are formed into handles 3. At the forward end are journaled the wheels 4, which preferably

extend a little beyond the end of the frame. The frame is provided with the usual front guard 5. Upon the inside of the said rails is secured a plate 6, which is adjustable by means of bolts and slots 7 8, such plates being placed opposite to each other. Extending below each of the rails is a semicircular extension, shown in Fig. 1 as an ear 9 on the plate 6. The truck is provided with two pivoted supporting-legs 11, and means are provided for limiting the swing of said legs, as adjustable brackets 12, each preferably provided with a slot through which passes a bolt 13, by which it can be secured in its adjusted position. The upper end of the bracket is recessed on the arc of a circle to meet and fit the rounded ear 9 when the bracket is at its upward limit. The ends of the arms formed by the recess in each bracket form stops which engage with the rails 1 and limit the movement of the legs on their pivots. Each leg is made in two parts, so as to be extended

when necessary, and the said parts are rabbed together, as shown in Fig. 3, where 11^a indicates the extension of the leg. The connection between the two parts of the legs is made by means of slots and bolts 14. The legs are braced by a frame 15, which is connected to them near their upper end by a rod 16. It is further secured by the intermediate rod 17, which passes through both sections of the leg and through the brace. It will be understood that the legs are tied together by the frame 15 and that the extension of each leg is adjustable and can be held at any point or adjustment by nuts upon the rods or bolts 17 and 14. Springs 18 are connected to the legs and also to some fixed part of the frame of the truck—as, for instance, the forward cross-piece 2, as shown in Fig. 2. These springs always tend to pull the legs toward the front of the truck. Connected to each leg is a rod 19, which extends along the side rail of the truck toward the rear and terminates in the handle 21, which is in convenient reach of the operator. The side rails are provided with guides 22 23 for these rods, and means are provided for locking the legs in any desired angular position, as the adjustable stops 24, which are held in position on the rod by set-screws. The guide 22 is preferably provided with rubber buffers 25. The legs should also be provided with rubber tips 26 in order to avoid injury to carpets in cases where the truck is employed for moving baggage or freight within houses.

In ordinary use upon substantially level surfaces this truck operates in the ordinary way of such trucks. It is well known that it is impossible to carry the ordinary baggage-truck with its load up a flight of stairs, and consequently the baggage or freight must be carried by hand under those circumstances. By my invention the truck with its entire load can be caused to move up a flight of stairs or several of them under the control of a single operator.

In operating the truck under ordinary circumstances in railroad-stations, &c., where it is simply used to transfer baggage and freight from one point to another on substantially level surfaces, the rods 19 are pulled to the rear, so as to bring the legs to such an angle that they will be out of the way. In this case the truck can be used like any ordinary truck. Under these circumstances the rod 19 and the leg can be locked in a fixed position by means of the adjustable stops 24.

Since this truck is especially adapted for climbing stairs with its load, a different kind of operation takes place in these conditions. In the first place the stops 24 will be moved upon the rod 19, so as to allow a considerable range of movement for said rod. On approaching a flight of stairs the forward carrying-wheels are brought up against the bottom step, and the legs are caused to move forward either by means of the spring 18 or by being pushed forward by the rod 19. The operator then lifts up the handles, which allows the legs to swing forward to the position indicated by line *y y* in Fig. 2, bringing the fulcrum or point of support near the forward end of the truck. The operator now pushes down and forward upon the handles, whereupon, owing to the favorable leverage, the wheels will easily mount the first step, while the legs assume the position of the line *z z* of Fig. 2, because the truck-frame and the load has been swung bodily forward upon the said first step. The operator then raises the handles, which again allows the legs to move forward and furnish the same favorable fulcrum-point. He now pushes down and forwardly on the handles, which causes the carrying-wheels to move easily upon the second step. Thus I gain two steps of the flight while the legs remain upon the floor. In the next operation the operator lifts the handles, which action allows the legs to swing forward and rise upon the first step, the carrying-wheels being upon the second step. He now lowers the handles and pushes forward, when the same operation that has before been described takes place, and the truck-frame and carrying-wheels swing easily forward upon the third step. In this way the truck with its load can be caused to ascend flights of stairs of any length, and hence heavy loads can be moved into houses and up the stairs in said houses without removing them from the truck. It follows from what has been described that loads can be taken downstairs with equal facility, the operation being simply reverse so far as the manipulation of the legs is concerned, and the successive fulcrums are made from step to step downwardly instead of step to step upwardly.

I do not limit myself to the specific constructions and arrangements herein described and shown in the drawings, as I desire to avail myself of such modifications and equivalents as fall properly within the spirit of my invention.

Having thus fully described my invention, what I claim as new, and desire to secure by Letters Patent, is—

1. In a truck, a wheel-supported carrying-frame provided with handles, supporting-legs pivotally secured to the frame intermediate its length, adjustable means between the legs and the frame, for limiting the movement of said legs, and means adjacent to said handles for moving the legs. 60

2. A truck frame and wheels, in combination with supporting-legs hinged to the frame behind the wheels, rods connected to said legs and extending along the handles and means for locking said rods to the handles and for releasing said rods, whereby the legs can be held in any position to form supports, and can also be released and caused to swing so as to vary their angular relation to said frame, substantially as and for the purposes set forth. 70

3. In a truck, a wheel-supported frame provided with handles, depending semicircular extensions on the side rails of the frame, supporting-legs pivotally secured to the frame intermediate its length, a rod from the legs to the handles for swinging the legs on their pivots, and adjustable stops for locking the legs against movement in any adjusted 80 position. 85

4. In a truck, a frame, carrying-wheels journaled therein, extensible two-part supporting-legs pivoted to said frame behind the carrying-wheels so as to form variable fulcrums, and means for changing the angular relation of said legs to said frame. 90

5. In a truck, the frame composed of side rails and cross-pieces, carrying-wheels journaled in said frame, plates secured to said side pieces behind the carrying-wheels and having depending circular ears, legs pivoted in said ears, and a bracket on said legs adapted to fit said circular ears. 95

6. In combination with a truck-frame and its carrying-wheels, pivoted legs, a rod connected to said legs, guides for said rods and adjustable stops on said rods coöperating with said guides for limiting their motion. 100

In testimony whereof I have affixed my signature, in presence of two witnesses, this 16th day of November, 1904. 105

DAVID H. ROWE.
